UNITED STATES PATENT OFFICE

GABRIEL VILLA, OF BOGOTA, COLOMBIA

CRUSHING MILL

Application filed April 18, 1929. Serial No. 356,181.

This invention relates to mills and while capable of general use, the present invention is directed more particularly to a mill for crushing and extracting the juice from sugar cane.

Mills of this character generally involve a plurality of rolls carried on shafts that are mounted in suitable bearings and adjustable toward and from each other. Due to the extremely heavy pressure required for the crushing of the cane, excessive stresses are imposed on the bearings which cause rapid wear and inefficient operation of the machine.

These machines, being operated in localities where the atmosphere is hot and humid, and the nature of the material handled being of an acid character, provides a problem of lubrication and efficient operation of the machine of a most serious character.

It is the primary object of the present invention to provide a mill wherein the shafts that carry the crushing rollers shall be non-rotatably mounted and which may be easily and quickly adjusted for the desired pressure.

Another object is to provide a mill wherein the crushing rolls shall be journaled on oversize bearings that are completely enclosed so that the bearing in addition to being ample in size to withstand the enormous stresses imposed thereon by the crushing rolls, shall also be sealed against the juices and foreign materials passing through the mill.

A further object is to provide a mill of this general character which shall be constructed in such manner that inexperienced operators may easily and quickly adjust any of the rolls or replace them if such becomes necessary.

A still further object is to provide a mill which shall be exceedingly simple in construction, highly efficient in operation, and which shall consist of few parts that are inexpensive to manufacture.

With these and other objects in view, the invention consists in the various novel features of construction and arrangement or combination, all of which will be fully described hereinafter and pointed out in the claims.

In the drawings accompanying and forming a part of this application,

Fig. 1 is a side elevation of a machine constructed in accordance with my invention;

Fig. 2 is a top plan view thereof;

Fig. 3 is a horizontal sectional view taken on the line 3—3 of Fig. 1;

Fig. 4 is a longitudinal sectional view through one of the idler rolls; and

Fig. 5 is a fragmentary detail of the rollers showing an enlarged view of the projections thereon.

A mill constructed in accordance with my invention comprises a base 1, substantially oblong in plan view and which is formed with a depression 2 defining a receptacle for the juices that are pressed from the cane. One side of this base is fitted with a discharge spout 3 so that the juices may drain from the depression. Rising from opposite sides of the base are plates 4 which serve as supports for the crushing rolls and associated parts. A pair of spaced horizontally disposed idler roll shafts 5 extend between the plates 4, and each shaft projects through elongated slots

7 in said plate as clearly shown in Fig. 1. Mounted on each shaft in spaced relation are a pair of ball bearings 8 which are disposed in recesses 9 formed in each end of the idler roll. As shown particularly in Fig. 4, each

idler roll 6 is formed with a hollow central portion and the aforementioned recesses 9 which receive the ball bearings and also suitable spacing collars 10. The bearings 8 each engage a shoulder 11 in the roll and a spacing

collar 10 is interposed between each bearing and its respective side plate. Each idler roll is provided with a plurality of circumferentially disposed grooves 12 and projections 13 which cooperate with longitudinally disposed

grooves 14 and projections 15 formed on the driving roller 16 to effectively crush the material passing therethrough.

The outer end portions of each of the idler roll shafts 5 are provided with horizontally disposed bores 18 which are adapted to receive horizontally disposed rods 19. Each rod 19 is formed with an enlargement 20 at its central portion and the outer ends of said rod are threaded to receive adjusting nuts

21. The enlargement 20 on each rod is received between spaced vertically disposed blocks 22 that project from the side plate 4, and these blocks are preferably formed with 5 horizontally disposed grooves 23 to receive the rod 19.

From the construction thus far described, it will be apparent that each idler roll together with its bearings and spacing collars 10 may be assembled as a unit and then placed in position in the machine. The end portions of the shafts 5 being received in the slots 7 of the side frames and the threaded end portions of the rods 19 will pass through the bores 18 15 in said shafts. By adjusting nuts 21 on the rods 19, the idler rolls may be moved toward each other to increase the pressure on the material passing through the machine, or said rolls may be permitted to be retracted 20 to decrease the pressure on the material. It will also be noted that the enlargement 20 engaging the blocks 22 permits each roll to be adjusted independently of the other.

Interposed between the idler rolls 6 is a 25 guide member 25 which bridges the gap between these rolls. This member is provided with downwardly turned end portions having elongated apertures 26 therein and through which passes a shaft 27 that is 30 mounted in suitable apertures in the side plates 4. The guide member 25 is thus free to move vertically and fill the gap between the guide rolls for each adjustment of said rolls.

35 Journaled above the guide rolls is a driving roll denoted generally at 30. As shown particularly in Fig. 3, this roller is formed with a hollow central portion and recessed ends, the latter receiving bearings 31 therein. A spacing and sealing collar 32 is also positioned in one of said recesses and is interposed between the bearing and side plate 4 and is keyed to shaft 35. The opposite end recess in the roller receives the hub portion 40 of a gear 34 that is journaled on a shaft 35 which extends through the roller and between the side plates 4. The end of roller 30 and the abutting surface of gear 34 are each 45 formed with interengaging projections and depressions denoted generally at 36 to provide a driving connection therebetween.

50 Meshing with gear 34 is a drive pinion 37 which is keyed to a drive shaft 38 that is journaled between the side plates 4. This drive shaft projects beyond one of the end plates 4 and is fitted with a pulley 39 or other suitable driving connection.

In order to strengthen the side frames and 55 impart rigidity to the structure as a whole I provide transverse brace rods 40 which extend between the plates 4 and are anchored thereto by nuts 41. These rods also serve to support feed and discharge troughs 42 and 43 respectively.

60 55 In operation, the cane or other material is

fed to the rollers by feed trough 42, the idler rolls having previously been adjusted as explained above. The horizontal ribs and depressions in feed roller 30 and the circumferential ribs and depressions in the idler rolls serve to thoroughly crush every fiber 70 of the cane passing therebetween. The cane passes between the feed roll 30 and one idler roll, thence across the guide member 25 and out between the feed roll and other idler roll to the discharge trough 43. The juices extracted during the crushing operation drain to the depression 2 in the base and are discharged from spout 3 to any suitable receptacle.

75 The peculiar construction of the idler and feed rolls renders them readily adjustable by inexperienced persons as it is only necessary to tighten or loosen the nuts 21. Furthermore, the use of stationary shafts permits the use of oversized bearings which are capable of withstanding the great stresses imposed thereon and also allows the bearings 80 to be entirely enclosed within the rolls and sealed from contact with the juices. The hollow rolls provide large lubricant reservoirs which allow the bearing to be properly lubricated over an extended period of time and hence require little attention. The construction of the machine permits assembling or 85 disassembling the same in minimum time and by inexperienced persons as the only adjustment required is accomplished by rotating nuts 21.

90 From the foregoing it will be clear that 100 one of the advantages inherent to the crushing mill of this invention is the possibility of using a relatively light frame construction. Heretofore the end frames of crushing mills have necessarily been of extremely 105 sturdy construction and correspondingly heavy in weight because of the fact that the bearings for the crushing rolls were carried directly on these end members. In contrast to such old forms the bearings are no longer 110 to be mounted on the end frame members and the end members merely support stationary axles with consequent reduction in load, stress and strain. The frame of the 115 machine may thus be of much lighter construction than formerly and with great saving of expense.

120 What I claim is:

1. A mill of the character set forth comprising a support, a plurality of horizontally disposed parallel shafts non-rotatably mounted in said support, rolls journaled on said shafts, rods engaging certain of said shafts, and means carried by said rods and engaging said shafts to adjust the same toward 125 and from each other.

2. A mill of the character set forth comprising a support, a pair of horizontally disposed shafts slidably but non-rotatably mounted in said support, a roll journaled 130

on each of said shafts, and connections between said shafts for adjusting the same toward and from each other.

3. A mill of the character set forth comprising a support, a pair of horizontally disposed shafts slidably but non-rotatably mounted in said support, a roll journaled on each of said shafts, and means interconnecting each of said shafts for adjusting the same independently toward and from each other.

4. A mill of the character set forth comprising a support, a pair of horizontally disposed shafts slidably but non-rotatably mounted in said support, a roll journaled on each of said shafts, a pair of rods arranged in spaced relation and interconnecting said shafts, and means carried by said rods and engaging said shafts for adjusting the same toward and from each other.

5. A mill of the character set forth comprising a support, a pair of horizontally disposed shafts slidably but non-rotatably mounted in said support, a roll journaled on each of said shafts, bearings interposed between each roll and its respective shaft and lying wholly within the roll, and a pair of rods arranged in spaced relation and interconnecting the end portions of said shafts, said interconnection between said rods and shafts including means for adjusting said rolls toward and from each other.

6. A mill of the character set forth comprising a base, side plates rising from said base and having horizontally disposed slots therein, spaced parallel shafts extending between said side plates and positioned in said slots, means interconnecting said shafts to prevent rotation of the same and for adjusting said shafts toward and from each other, and a roll journaled on each shaft.

7. A mill of the character set forth comprising a base, side plates rising from said base and having horizontally disposed slots therein, a plurality of shafts carried by said side plates and non-rotatably mounted therein, a roll journaled on each of said shafts, certain of said shafts being positioned in said slots, rods interconnecting the last mentioned shafts, means interconnecting said rods and side plates to prevent longitudinal movement of said rods, and means for adjusting said shafts along said rods.

55. 8. A mill of the character set forth comprising a base having a recess therein for the reception of liquids, side plates rising from said base and having horizontally disposed slots therein, a pair of shafts carried by said side plates and positioned in said slots, a third shaft non-rotatably mounted in said side plates and disposed in operative relation to said pair of shafts, a roller journaled on each shaft, bearings interposed between each shaft and its respective roller, said bearings lying

wholly within said rollers, and means interconnecting said pair of shafts for moving the same toward and from each other.

In testimony whereof I affix my signature.
